INVENTOR

SAMUEL W. LUITWIELER

Harold S. Stonebraker,
BY
ATTORNEY

UNITED STATES PATENT OFFICE.

SAMUEL W. LUITWIELER, OF ROCHESTER, NEW YORK.

CAM AND SPINDLE CONSTRUCTION.

Application filed July 9, 1923. Serial No. 659,398.

To all whom it may concern:

Be it known that I, SAMUEL W. LUITWIELER, a citizen of the United States of America, residing at Rochester, in the 5 county of Monroe and State of New York, have invented certain new and useful Improvements in Cam and Spindle Constructions, of which the following is a specification.

10 My invention relates to a cam and spindle assembly, and has to do more particularly with mounting one or more cams on a spindle so as to afford a strong, rigid, and firmly tied unitary structure.

15 A further object of the invention is to provide an arrangement that can be readily and economically manufactured, and which lends itself to a practical assembly, especially adapted for use in pump and engine 20 construction.

Other objects and advantages of the invention will appear more clearly from the following description, when read in conjunction with the accompanying drawing, 25 the novel features being pointed out in the claims following the specification.

In the drawing:

Figure 1 is an end elevation, with the supporting spindle in section, of mechanism 30 constructed in accordance with a preferred embodiment of the invention;

Figure 2 is a longitudinal vertical sectional view on line 2—2 of Figure 1;

Figure 3 is a transverse vertical sectional 35 view on line 3—3 of Figure 2, and

Figure 4 is an end view of a modification.

The invention includes a divided spindle embracing opposite spindle portions 1 and 40 2 which include end plates 3 and 4, preferably formed integral with the spindle portions 1 and 2. The end plates 3 and 4 are also provided with annular locking portions 5 and 6 consisting of alternately arranged 45 recesses and projections, and in the arrangement illustrated in Figures 1 to 3, each annular locking portion on the end plates includes three recesses and three projections for locking cooperation with the cams, as 50 will appear momentarily.

Arranged between the end plates 3 and 4 are cams 7, three such cams being disclosed in the illustrated embodiment, arranged symmetrically about the spindle for 55 cooperation with rollers 8, as usual in cam-

driven machinery. Each cam 7 is provided on its opposite sides with annular locking portions or collars 9, said locking portions embodying alternately arranged recesses and projections as on the end plates 3 and 4 previously mentioned. The locking recesses and projections are so disposed on the respective end plates and cams as to permit of interlocking engagement between adjacent faces of the cams, and between the end plates and adjacent cams, while retaining the symmetrical relationship of the cams to the spindle on which they are mounted. The arrangement of Figure 4 differs from the previously described arrangement, in that it includes only two interlocking recesses and projections on each annular locking portion, instead of three.

The cams are held thus assembled by suitable connecting means, preferably consisting of rods 10 passing through openings in the end plates and in the annular locking portions of the cams and held in place by nuts 11. 12 is a guide or centering rod supported in openings in the spindle portions 1 and 2 centrally thereof and passing through corresponding openings in the respective cams, thus serving to insure proper centering of the cams with respect to the spindle and contributing to a more rigid and unitary construction. The parts can be readily taken apart or assembled, and while the mechanism which I have disclosed can be employed in the attachment of a single cam, it is particularly adapted to assembling a series of cams on a spindle, where rigidity and strength are important factors to be considered.

While I have described the invention with reference to a particular construction, it is not limited to the details disclosed but may be modified or otherwise adapted without departing from the fundamental features of the improvement, as comprehended by the following claims.

I claim:

1. The combination with a divided spindle including oppositely disposed end plates, of a cam located between said end plates and having interlocking connection therewith, and attaching means for the cam and end plates.

2. The combination with a divided spindle including oppositely disposed end plates, of a cam located between the end plates and

for interlocking with one of the end plates, and attaching means for the cam and end plates.

3. The combination with a divided spindle including integral end plates, of a plurality of cams positioned between the end plates and having interlocking connection with said end plates and with each other, and means for attaching the cams and end plates together.

4. The combination with a divided spindle including end plates, of a plurality of cams located between the end plates and provided with annular locking portions on opposite sides including alternately arranged recesses and projections for interlocking cooperation with adjacent locking portions, the end plates having corresponding locking portions for engagement with the adjacent cams, and attaching means for the cams and end plates.

5. The combination with a divided spindle including end plates, of a plurality of cams located between the end plates and provided with annular locking portions on opposite sides including alternately arranged recesses and projections for interlocking cooperation with adjacent locking portions, the end plates having corresponding locking portions for engagement with the adjacent cams, a guide rod alined centrally of and supported in the opposite por-

tions of the spindle, said rod passing through openings in the cams, and attaching rods extending through openings in the annular locking portions of the cams and end plates for securing said parts together.

6. The combination with a divided spindle including integral end plates, said end plates having annular locking portions with alternately arranged recesses and projections, of a series of cams located between the end plates and having annular locking portions on opposite sides with alternately arranged projections and recesses for cooperation with corresponding locking portions on the adjacent end plate or cam, a centering rod arranged centrally of and supported in the opposite portions of the spindle and passing through openings in the cams, and a series of attaching rods extending through openings in the annular locking portions of the cams and end plates for securing said parts together.

7. The combination with a divided spindle, of a series of cams having interlocking connection with each other, the end cams having interlocking connection with the adjacent parts of the spindle, and means for securing the cams and spindle together.

In witness whereof, I have hereunto signed my name.

SAMUEL W. LUITWIELER.
